UNITED STATES PATENT OFFICE.

OTIS O. WHEELER, OF CHIPPEWA FALLS, WISCONSIN.

ADJUSTABLE DRAWING-TABLE.

1,258,510.

Specification of Letters Patent.

Patented Mar. 5, 1918.

Application filed May 2, 1917. Serial No. 165,897.

To all whom it may concern:

Be it known that I, OTIS O. WHEELER, a citizen of the United States, and resident of Chippewa Falls, in the county of Chippewa and State of Wisconsin, have invented 5 certain new and useful Improvements in Adjustable Drawing-Tables, of which the following is a specification.

This invention relates to office and school 10 furniture and has more especial reference to an improved drawing table.

The invention has for its dominant object 15 to provide a drawing table, the top of which can be adjusted vertically and to different angles, thereby enabling the user to arrange work upon the same in a manner to facilitate preparation thereof.

It is also an object of the invention to provide means whereby the forward or rear 20 sides of the table top may be adjusted vertically or both sides may be adjusted collectively.

Among other aims and objects of the invention may be recited, the provision of an 25 article of furniture of the character mentioned with a view to compactness, and in which the number of parts are comparatively few, the construction simple, the cost of production small and efficiency and operation high.

Other objects will be in part obvious and in part pointed out hereinafter.

The invention accordingly consists in the 35 features of construction, combination of elements and arrangement of parts which will be exemplified in the construction herein-after set forth and the scope of the application of which will be indicated in the following claims.

40 In the accompanying drawings, wherein is shown one of various possible embodiments of my invention,

Figure 1 is a top plan of the improved table having one portion of its top broken 45 away;

Fig. 2 is a side elevation thereof with a portion of the table top broken away;

Fig. 3 is an end elevation with a portion 50 of the side wall of the table broken away; and

Fig. 4 is a detail in section of the adjusting means locking device.

Similar characters of reference designate 55 corresponding parts throughout the several views of the drawings.

Referring now more specifically to the drawings, there is provided a base or body portion designated in its entirety by the numeral 1 and comprising a four walled structure, having formed in certain of its walls, 60 a plurality of drawer receiving shelves whereby drawers indicated by the numeral 2 may be slid thereinto. A second compartment is formed within the body or base portion of the desk and is normally closed by 65 means of a hinged door 3, the same serving as an efficient compartment for receiving drawing boards and the like. A suitable opening is formed within the rear wall of the desk face and has arranged therein a 70 hinged case 4 having a plurality of pockets formed therein by the arranging of partitions, whereby large drawings can be conveniently placed or filed therein. It is to be understood, that the various drawers 2 75 serve as means for receiving the instruments of the user and for receiving the smaller sheets or drawings, etc.

A partition 5 is arranged within the desk base 1 preferably intermediate its ends and 80 serves not only as an additional support or brace for the structure but also as means for supporting the table top adjusting means which are hereinafter more fully described, a suitable transversely disposed cross bar 6 85 being arranged upon the same.

Movably positioned upon the upper or top portion of the desk body 1 is a top 7 carrying upon its underside a plurality of brackets, one of which includes longitudinally aligned arms designated 8 while the other includes a plurality of radially disposed arms 9, the intermediate one having an enlarged web portion in which an elongated slot 10 is formed. In this connection, 95 it will be noted that the several brackets are arranged adjacent the forward and rear sides of the table top.

Vertically disposed screw threaded rods 11 and 12 are supported upon the cross bars 100 6 of the intermediate portion 5 and extend through the elongated internally screw threaded hubs of beveled gears 13 and 14, while heads or brackets 15 and 16 adapted to be received by the brackets carried on 105 the under side of the table top 7 are arranged on the upper ends. A pin 17 is arranged upon the head 15 and is slidably engaged in the elongated slot 10 of the web portion of the central bracket arm 9, while 110

the head 16 is pivotally engaged between the longitudinally alined arms 8 of the remaining bracket.

Boxings 18 are secured to the intermediate portion 5 and slidably receive the several hubs of the gears 13 and 14 therein. Hence, upon rotation of the gears 13 and 14 the same will be caused to raise or lower depending upon the direction in which they are turned.

Bearing brackets 19 are supported within the cross bar 6 and rotatably support shafts 20 and 21, the shaft 20 extending through a bearing collar arranged in the forward wall 15 of the desk body 1 while the shaft 21 is formed in sections, the purpose of which will be presently apparent. Gears 22 and 23 are mounted upon the adjacent extremities of the sectional shaft 21 and are adapted 20 to be engaged by a gear 24 carried upon the adjacent end of the shaft 20, while on the opposite extremities of the sections of the shaft 21, beveled gears 25 and 26 are mounted and are constantly in mesh with the bevel 25 gears 13 and 14 carried upon the screw threaded rods 11 and 12. The shaft 20 is slidably mounted within the bearing brackets 19 and carries thereon an adjustable stop 30 collar 27 whereby movement of the same will be limited; a crank handle 28 being secured to its outer end for an obvious purpose.

To lock the slidable shaft 20 in an adjusted position an annular groove 29 is formed therein and is adapted to be engaged by a lip portion carried upon one end of a lever 30 pivoted upon the forward wall of the desk body adjacent the bearing collar as at 31, a spring being engaged with the 40 free end of the lever for normally forcing said lip portion inwardly.

An arm 32 having a screw threaded bore formed in its outer extremity is pivotally engaged with a vertically arranged rod 33 secured to the intermediate portion 5 of the desk body and serves as means for supporting a seat 34 having a screw threaded shank 35 secured to the under side of the same. A stop collar 36 is also arranged 50 about the vertical rod 12 and is provided with a set screw 37 whereby the same can be slid on the rod 33 and may be locked in various positions on the rod 12, thus, maintaining the arm 32 in an adjusted position. Obviously, in addition to adjusting the stop 55 36 for varying the height of the seat 34, the same may be also rotated whereupon the screw threaded shank 35 will cause adjustment thereof.

60 In operation, when it is desired to raise the rear side of the table top 7 the slidable shaft 20 is forced inwardly until the stop collar 27 engages the adjacent bearing bracket 19. At this time, the gear 24 will be in mesh with the gear 23 and as a conse-

quence, upon rotation of the shaft, the rear side of the table top will be raised or lowered due to rotation of the screw threaded hub of the gear 14 about the screw threaded rod 11, the sliding connection between the head 15 carried by the said rod and the top allowing the latter to properly adjust itself thereon. Should it be desired to adjust the forward side of the table top, the shaft 20 is now moved so as to bring its gear 24 into 70 mesh with the gear 22. Hence, upon rotation of the shaft, the screw threaded hub of the gear 13 arranged on the rod 12 will thereby effect the desired adjustment of the forward side of the table top. In the event 80 that the user desires to adjust the forward and rear sides of the table top collectively the shaft 20 is now moved to a position whereat the gear 24 will mesh with each of the gears 22 and 23 and is locked in such 85 position by means of the lever 30, the lip portion of which engages the annular groove 29 formed in the said shaft 20. With this adjustment, it will be appreciated by workers in the art, that the table top may 90 have its position varied to facilitate the arranging and preparation of drawings thereon.

The construction due to the arrangement of the various compartments therein also 95 serves as an efficient article of furniture for filing purposes wherein drawings, instruments, etc., may be kept.

Manifestly, the construction shown is capable of considerable modification and such 100 modification as is within the scope of my claims, I consider within the spirit of my invention.

I claim:

1. A table including a top, a plurality of 105 vertically disposed screw threaded rods carried by said table, brackets mounted upon the upper ends of said rods having pivotal and slidable engagement with the top, adjusting means rotatable on the rods, a sectional shaft connected to the adjusting means, and shiftable means engageable with the sectional shaft for rotating the adjusting means independently or collectively.

2. A table including a top, a plurality of 110 spaced screw threaded rods arranged on the table, brackets carried upon the upper ends of said rods having pivotal and slidable engagement with the forward and rear sides of the top, adjusting means rotatable on said rods, a sectional shaft mounted on the table and connected to the adjusting means, shiftable means engageable with the sectional shaft for rotating the adjusting means independently or collectively, and an adjustable 115 seat pivotally supported on the table.

3. A table including a top, a plurality of 120 spaced vertically disposed screw threaded rods arranged in bearings on said table, brackets swivelly connected with the upper 125

ends of said rods and having pivotal and 5 slidable engagement with the top, adjusting means rotatable on the rods, a sectional shaft connected to the adjusting means, and shiftable means engageable with the sectional shaft for rotating the adjusting means independently or collectively.

4. A table including a top, a plurality of vertically disposed screw threaded rods carried by said table, brackets swivelly mounted upon the upper ends of said rods having

pivotal and slidable engagement with the top, gears mounted on the upper ends of the rods, a sectional shaft carrying gears meshing with said first mentioned gears, and 15 means interconnected with the sectional shaft and shiftable thereon for independently or collectively rotating the same.

In testimony whereof, I affix my signature hereto.

OTIS O. WHEELER.
